INVENTOR

WILSON C. WILLIAMS.
By Milton E. Robinson

ATTORNEY.

UNITED STATES PATENT OFFICE.

WILSON C. WILLIAMS, OF UTICA, NEW YORK.

FIRE-ESCAPE.

SPECIFICATION forming part of Letters Patent No. 596,198, dated December 28, 1897.

Application filed April 12, 1897. Serial No. 631,678. (No model.)

To all whom it may concern:

Be it known that I, WILSON C. WILLIAMS, of Utica, in the county of Oneida and State of New York, have invented certain new and useful Improvements in Fire-Escapes; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

Figure 1 shows a side elevation of my improved fire-escape. Fig. 2 shows parts of the device, partially in section, in perspective. Fig. 3 shows one of the parts of which the body of the device is formed, also in perspective, without being in section in any part. Fig. 4 shows a section taken on line A B of Fig. 5, showing the inner face view of the parts shown. Fig. 5 shows a section taken on a vertical central line, omitting the friction-posts and bar in the lower end of the device. Fig. 6 shows a section of the completed device. Fig. 7 shows details of a sheave having projecting arms on one side. Fig. 8 shows the same as Fig. 7 on a quarter-turn from the position shown in Fig. 7. Fig. 9 shows a side elevation of a vibrating detent employed in the construction. Fig. 10 shows a plan view of the same. Fig. 11 shows an end view.

Referring to the reference letters and figures in a more particular description of the device, 1 and 2 indicate the two parts of the casing of the device. The upper portion of the casing part 2 is circular and provided with an internal serpentine groove 3, formed between the annular projections 3^a and 3^b. This annular groove 3 is adapted to receive the projecting ends 4^a 4^b of the vibrating detent 4.

The circular head portion of the device is adapted to receive the sheave 5 with its projecting arms 5^a, which projecting arms are adapted to receive the body portion of the detent 4. The casing parts are held together at their upper ends by a transverse bolt 6, which passes through an opening in the sheave 5 and through the opening 4^b in the detent 4. The opening 4^b is rounded out at either side, as shown in Figs. 9 and 10, so as to allow the detent to vibrate freely in following the ser-

pentine groove in the casing. The lower portion 1^a of the casing part 1 furnishes an outlet from the sheave, and the part 2^a of the casing part 2 furnishes a cover or closure for one side of this outlet. In the outlet portion is provided a friction device consisting of a longitudinal bar 7 with several transverse cross-bars 7^a, three being shown in the drawings. This friction device may be secured in position by rivet-like projections *a* on the ends of the cross-bar portions engaging in openings, as *b*, in the walls of the casing, and these rivet portions may be headed or not, as desired.

The rope or cord A' employed in connection with the device is entwined through the friction device, as shown, and passed around the sheave 5 and out of the outlet portion of the device and through the friction device again, a double rope or cord being employed.

The device is provided with a bail 8, which may consist of two parts formed on each part of the casing, as 8^a and 8^b, as shown.

In use the device operates as follows: The escape is suitably secured by the bail or otherwise in any desired position for use, as to the outside of a building or immediately inside of a window of a building, where it would be convenient for use. A person may then grasp one of the two parts of the cord or rope entering the device and throw his weight thereon, and as one part runs out the other runs in through the friction device, consisting of the bar 7 and the cross-bars 7^a, and thence around the sheave and out again through the friction device and causes the sheave to revolve. The friction caused by the friction device is sufficient to cause the cord or rope to bite sufficiently on the sheave to cause it to revolve without any material slipping of the cord or rope. As the sheave 5 revolves it causes the vibrating detent 4 to move around with it by reason of the arms 5^a 5^b inclosing the detent, as shown. The detent following the serpentine groove in the shell retards the movement of the sheave and thus regulates the speed with which the rope will run out. The amount of weight or load on the rope does not make any material difference, for the reason that the friction between the inner sides of the arms 5^a and the sides of the detent 4 increases as the weight on the

100

rope increases, and as it has to vibrate in following the serpentine groove under the influence of this friction the speed is regulated without reference to the load.

5 In order to enable the detent 4 to be introduced into the casing portion 2, there is provided in the shell an opening *x*, through which one of the projections 4^a may be temporarily projected, while the other projection 10 4^a of the detent is gotten into line with the serpentine groove, when the detent is moved into its central position in the circular portion of the casing, and a bolt 6 prevents it from at other times becoming engaged with 15 or projecting through the opening *x*.

It is evident that changes and modifications in and from the construction as illustrated and described may be made without departing from the equivalents of my construction.

20 What I claim as new, and desire to secure by Letters Patent, is—

1. In a fire-escape device a casing having a serpentine annular groove, a vibrating detent 25 running in the groove and a sheave having arms embracing the detent, substantially as set forth.

2. In a fire-escape device a casing having an annular serpentine groove and an outlet,

a vibrating detent running in the groove, a sheave having arms receiving the detent, substantially as set forth.

3. In a fire-escape device a casing having a crooked channel around its interior face, a sheave, a vibrating detent and means for connecting the sheave and detent, substantially as set forth. 35

4. In a fire-escape device, the combination of a shell having a serpentine annular groove and an outlet portion, a vibrating detent having 40 projections engaging in the serpentine groove, a sheave having arms embracing the detent and a friction device in the outlet portion of the casing, substantially as set forth.

5. The combination in a fire-escape device 45 of a casing having a crooked groove 3, a vibrating detent 4 having projections engaging in the groove, a sheave having projecting arms extending upon either side of the detent, and a rope friction device, substantially as 50 set forth.

In witness whereof I have affixed my signature in presence of two witnesses.

WILSON C. WILLIAMS.
